GAME BOARD

Mary Mariani, 1574 W. 3rd St., Brooklyn 4, N.Y.

Filed July 8, 1964, Ser. No. 80,757

Term of patent 3½ years

(Cl. D34—5)

The figure is a plan view of a game board showing my new design.

The game board is of conventional thickness.

I claim:

The ornamental design for a game board, as shown and described.
